CLAIM

The ornamental design for a stacking filing tray, as
shown and described.

DESCRIPTION

FIG. 1 is a top perspective view of a stacking filing tray
showing my new design, the additional trays depicted
by means of broken lines being shown for illustrative
purposes only and forming no part of the claimed de-
sign;

FIG. 2 is a bottom perspective view thereof;

FIG. 3 is a front elevational view thereof;

FIG. 4 is a right side elevational view thereof, the left
side elevational view being a mirror image;

FIG. 5 is a rear elevational view thereof; and,

FIG. 6 is a bottom plan view thereof.

FIG. 3
